UNITED STATES PATENT OFFICE

144,005

DESIGN FOR A FIGURE TOY

William Boyd Thomas, Kansas City, Mo.

Application August 6, 1945, Serial No. 121,257

Term of patent 7 years

(Cl. D34—15)

To all whom it may concern:

Be it known that I, William Boyd Thomas, a citizen of the United States and a resident of Kansas City, in the county of Jackson, State of Missouri, have invented a new, original, and ornamental Design for a Figure Toy, of which the following is a specification, reference being had to the accompanying drawing, forming a part thereof.

In the said drawing—

I claim:

The ornamental design for a figure toy, substantially as shown and described.

WILLIAM BOYD THOMAS.
